US00D739008S

(12) **United States Design Patent**
Curran et al.

(10) **Patent No.:** **US D739,008 S**
(45) **Date of Patent:** **** Sep. 15, 2015**

(54) **POWERED AIR PURIFYING RESPIRATOR
UNIT COVER**

(71) Applicant: **3M INNOVATIVE PROPERTIES
COMPANY**, St. Paul, MN (US)

(72) Inventors: **Desmond T. Curran**, Nevilles Cross (GB); **Andrew Murphy**, Binchester Moor (GB); **Christopher N. Findlay**, Wheatley Hill (GB)

(73) Assignee: **3M Innovative Properties Company**, St. Paul, MN (US)

(**) Term: **14 Years**

(21) Appl. No.: **29/484,946**

(22) Filed: **Mar. 14, 2014**

(51) LOC (10) Cl. **29-02**

(52) U.S. Cl.

USPC **D24/110**

(58) **Field of Classification Search**

USPC D24/107, 108, 110, 110.1-110.6, 111, D24/164, 185, 186

CPC ... A61M 16/208; A61M 16/06; A61M 16/20; A61M 2202/0208; A62B 18/00; A62B 18/02; A62B 18/025; A62B 18/10; A62B 18/08; A62B 23/02

(57) **CLAIM**

The ornamental design for a powered air purifying respirator unit cover, as shown and described.

DESCRIPTION

FIG. 1 is a perspective view showing the new design for a powered air purifying respirator unit cover;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken line showing of the powered air purifying respirator unit illustrates the environment of the claimed design and forms no part thereof.

1 Claim, 3 Drawing Sheets
